UNITED STATES PATENT OFFICE

JOSEPH P. HOLT, OF MERION, PENNSYLVANIA, ASSIGNOR TO ABERFOYLE MANUFACTURING COMPANY, OF CHESTER, PENNSYLVANIA, A CORPORATION OF PENNSYLVANIA

METHOD OF TREATING YARN

No Drawing.

Application filed October 18, 1930. Serial No. 489,714.

This invention relates to the softening of yarn. While the invention will be described in connection with the formation and treatment of cotton yarn, it is understood that the invention is not limited thereby, but will apply to yarns other than cotton.

In the manufacture of cotton yarn, raw cotton is carded and spun into strands. The fibres of the strands are bound together by the spinning so that they become twisted together, each strand aligning closely with its neighbors.

This single strand, as twisted in the spinning, is oftentimes used as yarn in the formation of finely woven or knitted materials, while in other instances, a plurality of these strands are twisted together to produce a multiple strand yarn.

The raw cotton yarn either in a single strand or composed of a plurality of strands, is usually bleached, mercerized and dyed, or may be treated with a combination of any of these steps in order to produce the finished article.

It has been found that yarns are stiffened or made harder by any of these treatments and, consequently, are less adaptable to the knitting machine than would be the case if softer.

Various processes have been advanced for the treatment of finished yarn in order to soften the same and therefore render it more adaptable to the knitting machine.

The patent art abounds in processes of treating yarns to soften the same and usually consists of emulsifying or treating the same with conditioning oils, either prior to or during the step of "coning" the yarn.

It has also been suggested to beat or flay the finished yarns with tom toms or the like, for relieving it of its stiffness.

While all of these processes are helpful in varying degrees, none of them is capable of producing a perfect yarn for the purpose specified.

The object of this invention is to provide a process of mechanical treatment for softening yarn.

According to the invention, the yarn, after

treatment, is partially untwisted and then retwisted.

It is well-known that cotton in its raw state is quite soft and even the spinning of the same into strands does not materially harden the texture of the strands. However, when these strands are twisted together to form a multiple twisted yarn, the resulting yarn is somewhat harder in character.

This hardness is greatly intensified by dyeing, bleaching and mercerizing, which causes the fibres of the strands to become more closely aligned and also has the effect of causing the strands to adhere more closely to their neighbors.

The resultant product, either in the single strand or multiple strand yarn, is quite stiff, and the original softness of the cotton has almost entirely disappeared. The method employed for softening the yarn comprises the steps of partially untwisting the yarn and then retwisting the same with the same or lesser number of twists per inch.

In the case of the single strand yarn, this would be the untwisting of the fibres which compose the strand; while in the multiple strand yarn, it would comprise the untwisting of the strands and then the retwisting of the same. In the latter case, when the strands are untwisted, the fibres of each strand are somewhat agitated by the untwisting and, therefore, they will become looser and when the strands are again twisted, these fibres of the separate strands will take up somewhat new positions in the strand and, therefore the texture of the retwisted yarn will be entirely different than before untwisting.

For example, let us consider a single strand of yarn that is twisted about fifteen times to the inch. This is its condition when treated. In the untwisting of the yarn let us assume that it is untwisted so as to leave about four or five twists to the inch and then in the retwisting step, add about seven twists to the inch, bringing it to a little less than the former number of twists, or bringing it back to the original number of twists, or even giving it a greater number than the number of original twists.

In any instance, the fibres have been pulled apart and will assume new relations upon the retwisting of the same.

This is practically the same condition that will result in the case of the multiple strand yarn. When the strands are untwisted the fibres of the individual strands will be necessarily agitated and will, consequently, take up new relations with their neighbors and, therefore, when the retwisting of the strands is accomplished, the entire yarn will be softer in texture and will be more readily adaptable to the knitting machine.

While the invention is simple and quite easy to perform, it has been found that the result obtained is remarkable and particularly with mercerized and bleached cotton yarns where the chemicals used tend to stiffen the resulting yarn to a great degree. Samples of yarn treated according to this invention have been experimented with by manufacturers of knitted goods and such yarns have been found to have that high degree of efficiency long sought.

Of course, in the steps of untwisting and retwisting the yarn, ordinary twisting machines may be utilized and no claim is made for any of the mechanism used in carrying out this invention.

While the invention has been described in connection with the treatment of cotton yarn, it is not limited thereto, but may be used to advantage in softening wool and other yarns after treatment thereof.

Of course, the invention here described is not limited to any precise number of reductions in the original twisted yarn, nor to any precise number of retwists, nor is the invention limited to any treatment prior to the process here disclosed and, therefore, the invention is capable of wide latitude and application without departing from the subject matter thereof, as embraced in the following claims.

The invention is hereby claimed as follows:

1. The herein described process of softening cotton yarn after the same has been chemically treated, comprising the steps of partially untwisting the same, and then retwisting it.

2. The herein described process of softening twisted cotton yarn after mercerization, comprising the steps of partially untwisting the same, and then retwisting it.

3. The herein described process of softening multiple strand twisted cotton yarn after mercerization, comprising the steps of partially untwisting the strands thereof, and then retwisting the same.

4. The herein described process of producing soft cotton yarn, comprising the steps of twisting a plurality of spun strands, then chemically treating the same, then partially untwisting the strands, and then retwisting the strands.

5. The herein described process of producing soft mercerized cotton yarn, comprising the steps of twisting a plurality of spun strands, then mercerizing same, then partially untwisting the strands, and then retwisting the strands.

6. The herein described process of producing soft bleached cotton yarn, comprising the steps of spinning the cotton into a strand, then chemically bleaching the strand, then partially untwisting the strand, and then retwisting the strand.

7. The herein described process of producing soft bleached cotton yarn, comprising the steps of twisting a plurality of spun strands, then chemically bleaching the same, then partially untwisting the strands, and then retwisting the strands.

8. The herein described process of softening cotton yarn after the same has been chemically treated, comprising the steps of partially untwisting the same, and then retwisting it with a number of turns less than the original twist.

9. The herein described process of producing soft mercerized cotton yarn, comprising the steps of twisting a plurality of spun strands, then mercerizing the same, then partially untwisting the strands, and then retwisting the strands with a number of turns less than the original twist.

In testimony whereof I have signed my name to this specification.

JOSEPH P. HOLT.
